UNITED STATES PATENT OFFICE.

CHARLES S. MIDDLETON AND DREWIE B. THOMPSON, OF BLAKELY, GEORGIA.

COTTON-ELEVATOR.

1,240,752.

Specification of Letters Patent. Patented Sept. 18, 1917.

Application filed July 14, 1915. Serial No. 39,908.

To all whom it may concern:

Be it known that we, CHARLES S. MIDDLETON and DREWIE B. THOMPSON, citizens of the United States, residing at Blakely, 5 in the county of Early and State of Georgia, have invented certain new and useful Improvements in Cotton-Elevators; and we do hereby declare the following to be a full, clear, and exact description of the invention, such as will enable others skilled in the art to which it appertains to make and use the same.

This invention relates to cotton elevators, and has for an object to produce an elevator of improved type wherein and whereby cotton may be continually elevated and deposited in the gin feeders without interruption for permitting the cotton to fall from the screen or without interrupting the 20 flow of cotton.

A further object of the invention is to interpose between the usual suction fan and the usual flexible suction nozzle a trunk comprising two independent cotton-conveying ducts disposed between two independent air ducts isolated from each other but respectively communicating with the cotton ducts, and means to simultaneously and alternately open and close the cotton ducts 25 and their communicating air ducts so that the cotton carried into one cotton duct by the air suction is left in a dead space and permitted to fall into the gin feeder in substantially the usual and ordinary manner 30 when the suction is interrupted in a single cotton elevator.

With these and other objects in view the invention consists in certain novel features of construction, combination and arrangement of parts as will be hereinafter more fully described and claimed.

In the drawings:

Figure 1 is a top plan view of the horizontal conveyer portion or trunk of the elevator, parts of the housing being broken away to show the internal construction of the ducts.

Fig. 2 is a transverse sectional view through the cotton ducts showing the air ducts in end elevation as taken on line 2—2 of Fig. 1.

Fig. 3 is a transverse sectional view through both the air ducts and the cotton ducts taken on line 3—3 of Fig. 1.

Fig. 4 is a perspective view showing the top of the gin feeder with the air and cot-

ton ducts removed therefrom taken on line 4—5 of Figs. 2 and 3 looking downwardly.

Fig. 5 is a perspective view of the under side of the trunk taken on line 4—5 of Figs. 2 and 3 and looking upward.

Fig. 6 is a view in elevation of two gins with their feeders and a cotton elevator of the present type associated therewith.

Like characters of reference designate 65 corresponding parts throughout the several views.

The cotton elevator which forms the subject-matter of this application is used in conjunction with an exhaust fan of the 70 usual and ordinary type shown at 10 and a flexible section nozzle 11 also of the usual and ordinary type. The present invention resides in the horizontal portion or trunk disposed over the gins and gin feeders and 75 connected with the fan upon one side by an air duct 12 and upon the other side with the flexible nozzle by the cotton duct 13.

Where the trunk passes over the gins, 80 two of which have been indicated in dotted lines at Fig. 6 as 14, it branches to form the twin ducts 15 and 16 closed at their forward ends as at 15'. Switch valves 17 and 18 are hinged adjacent the branch of the cotton duct 13 and are connected to operate in unison by a link 19. One of the valve stems is provided with a crank arm 20 by which the valves 17 and 18 are actuated in unison to switch the flow of cotton alternately into the ducts 15 and 16. 90

At the other end of the trunk the air duct 12 branches to form the branch air ducts 21 and 22 which pass along outside the twin ducts as seen in Fig. 5 and have their rear ends closed at 21'. To control 95 the exhaust of air from the ducts 21 and 22 in unison with the flow of cotton to the ducts 15 and 16 a valve 23 is located at the branch of the air ducts as shown more particularly at Fig. 1 and is provided with a crank arm 24 to which is connected a link 25 extending also to the crank arm 20 whereby all of the valves 17, 18 and 23 are actuated in unison. The actuation of the valves may be, and in practice probably 100 will be, accomplished mechanically, but it may also be accomplished manually and means is shown at Fig. 6 for carrying out the actuation of the valves manually by extending the pintle of the valve 23 downwardly through the chute as shown at 26 and providing it with a crank arm as shown

at 27 in position to be engaged and operated manually.

Beneath the several branch ducts 15, 16, 21 and 22 a double gin feeder is employed 5 having the compartments 28 and 29 provided with cotton valves 30 and 31 and the usual and ordinary screens 33. The gin feeder is divided from top to bottom by a partition 34 so that each of the compartments 10 upon the opposite sides of such partition 34 is in communication with one of the branch cotton ducts, the latter being open at the bottom for this purpose as indicated at 16' in Figs. 3 and 5. The parting wall 15 34' between the two ducts is in air-tight contact with said partition 34, but the side walls of the ducts are wider and depend beneath the floor of the trunk as seen at 22' in Fig. 3, and the bottom walls of the air ducts are 20 spaced slightly from said side walls to leave openings 32. The latter are inclosed by offsets 32' in the walls of the feeder, and the offsets are connected with said compartments through the screens 33 as shown. It 25 follows that the communication between either air duct as 21 and its contiguous cotton duct 15 is downward from the latter, through the screen 33, upward within the offset 32', and through the opening 32 into 30 the air duct 21—rather than direct from the cotton duct through the screen into the air duct.

The cotton drawn into the branch cotton duct 15 as shown at Fig. 3 by the exhaust of 35 the air in the branch air duct 21 will of course fall into the compartment 29 except such portion thereof as gathers upon the screen 33, and this continues in the usual and ordinary manner as long as the branch 40 air duct 21 is under exhaust. When, however, the several valves 17, 18 and 23 are shifted to dotted line position as shown at Fig. 1 the cotton will be drawn into the branch duct 16 by reason of the exhausting 45 of the branch air duct 22, and the cotton duct 15 and air duct 21 will be dead permitting the cotton already gathered upon the screen 33 to drop into the compartment 29 past the cotton valve 31 in the usual and 50 ordinary manner. The parting wall 34' between the twin ducts and the coincident partition 34 form an air-tight barrier between

the ducts 16, 22 which are now at work and the ducts 15, 21 which are now dead; and we find it extremely effective to provide this 55 barrier in place of any gate or valve, since the least leakage through the latter would interrupt the successful action of the cotton. Being of a light, fluffy nature, it is easily subject to drafts, and in order to permit it 60 to drop out of the duct 15 and off of the screen 33, this side of the device should be absolutely "dead" as stated. Even the valve 30 is serviceable, because the suction within the ducts 16, 22 now draws this valve upward and closes it across the compartment 28 and prevents any suction at the lower end of the partition 34 which would interrupt the falling of the cotton through the compartment 29 and into the gin. 70

It will thus be apparent that each of the screens is under exhaust one-half of the time and the cotton is being fed through one of the branch cotton ducts one-half of the time and through the other one-half of the time, 75 the other half of the time each of said ducts being dead, permitting the cotton to fall into the feeder. It will also be apparent that the conveying of cotton through the nozzle and into the feeders will be continuous and without any interruption for permitting the screens to clear themselves as has heretofore been found necessary. 80

We claim:—

In a pneumatic cotton elevator, an intake 85 nozzle and an air tube alined therewith, a distributing trunk therebetween having parallel inner cotton ducts with a partition centered with the nozzle end, a valve chamber connecting said ducts and the nozzle, and 90 cotton valves for alternate engagement with the near end of the partition, lateral air ducts paralleling the cotton ducts, suction inlets in the bottom of said air ducts for communicating with an attached feeder, convergent air branches attached to the spaced 95 rear ends of the air ducts, and to the air tube, a single valve in said air branches, and connecting means between the cotton valves and the air valve. 100

In testimony whereof we affix our signatures.

CHARLES S. MIDDLETON.
DREW D. THOMPSON.
